UNITED STATES PATENT OFFICE.

CHARLES D. MORRIS, OF WASHINGTON, DISTRICT OF COLUMBIA, ASSIGNOR OF THREE-FIFTHS TO WILLIAM D. JUNKIN, OF SPOKANE, WASHINGTON, AND ONE-FIFTH TO JOSEPH B. SWINBURNE, OF WASHINGTON, DISTRICT OF COLUMBIA.

TELEPHONE RELAY OR REPEATER.

1,033,114.

Specification of Letters Patent. Patented July 23, 1912.

Application filed October 10, 1910. Serial No. 586,278.

To all whom it may concern:

Be it known that I, CHARLES D. MORRIS, a citizen of the United States, residing at Washington, in the District of Columbia, have invented a new and useful Telephone Relay or Repeater, of which the following is a specification.

This invention relates to relays or repeaters for use in long distance telephony, its primary object being the provision of a relay transmitter utilizing both a fixed and a movable electrode in connection with interposed granular carbon, and whereby the vibrations are accurately repeated and transmitted by the relay and the sounds produced at the receiving station are perfectly clear and free of the harshness or rasping quality of tone so noticeable in long distance telephony where the vibrations are transmitted through one or more relays each of which has two movable electrodes.

A further object is to provide a relay mounted within a casing having a lining of a material designed to prevent exterior magnetic waves from influencing the mechanism of the relay.

Another object is to provide a relay which is compact in construction and all the parts of which are readily accessible.

With the foregoing and other objects in view which will appear as the description proceeds, the invention resides in the combination and arrangement of parts and in the details of construction hereinafter described and claimed, it being understood that changes in the precise embodiment of invention herein disclosed can be made within the scope of what is claimed without departing from the spirit of the invention.

In the accompanying drawings the preferred form of the invention has been shown.

In said drawings:—Figure 1 is a plan view of the relay with its cap removed and the upper binding post in section. Fig. 2 is a central vertical section through the complete relay, the transmitter and the electro-magnet being shown in elevation. Fig. 3 is a plan view of the casing of the relay and of those parts within the casing and below the diaphragm. Fig. 4 is an enlarged central vertical section through the transmitter of the relay.

Referring to the figures by characters of

reference 1 designates a casing preferably cylindrical and formed of fiber, this casing being lined with aluminum or other suitable material, such as indicated at 2, for the purpose of shielding the contents of the casing from the influence of external magnetic waves. Attaching brackets 3 may be extended from the casing 1 and said casing may be provided, around its upper or open end portion, with an exterior channel 4 for the reception of the flange 5 formed upon the cap 6 of the casing.

A laminated permanent magnet 7 is secured within the casing 1 and has high resistance electro-magnets 8 mounted upon the poles thereof, these electro-magnets being electrically connected, as by means of conductors 9, to binding posts 10 and 11 secured upon the casing 1 as shown.

A diaphragm 12 of any preferred construction and material or materials, bears, at its periphery upon the casing 1 and is clamped thereon by means of arcuate holding strips 13 attached to the casing by screws or the like extending through the marginal portion of the diaphragm. These strips 13 are spaced apart at their ends so as to receive between them the thickened end portions 14 of a bridge 15 extending diametrically across the casing and diaphragm and having a central upwardly off set portion 16 located opposite the center of the diaphragm 12.

A transmitter button 17 is arranged within the central off-set formed by the bridge and comprises a fixed electrode 18 mounted within an inverted cup-like member 19, there being a stem 20 projecting from said member and into a sleeve 21, where it is secured by means of a set screw 22 or the like. Said sleeve has a reduced tubular extension 23 extended through the bridge and insulated therefrom by rings of mica or other suitable material such as indicated at 24. The free end of the extension 23 is preferably screw-threaded so as to be engaged by a nut 25 whereby the sleeve 21 and insulation may be securely held relative to the bridge.

A ring 26 is screwed into the open end of the member 19 and supports a diaphragm 27 of mica or other desired insulating material, this diaphragm carrying the movable electrode which, as shown particularly in Fig. 4 is preferably made up of two disks 28

secured upon opposite faces of the diaphragm 27 and also connected together, as by means of screws 29, one of the disks having a stem 30. Said stem projects through 5 and is secured to the center of the diaphragm 12 and has a conductor 31 secured to it and extending to a binding post 32. This binding post extends from the bridge 15 and is suitably insulated therefrom. The 10 sleeve 21, which practically constitutes a part of the fixed electrode 18 is electrically connected, as by a conductor 33 to a binding post 34 similar to the post 32 and which is insulated from the bridge 15. The two 15 binding posts 32 and 34 project through the cap 6 and are engaged by nuts 35 for securing the cap upon the casing 1. The binding nuts 36 are of course mounted on the terminals of these posts for the purpose of connecting these conductors to the posts. 20

It is of course to be understood that the space between the electrodes 18 and 28 is to be filled with granular carbon such as ordinarily employed in telephone transmitters.

25 What is claimed is:—

1. A telephone relay including a casing, a lining therein for shielding the contents of the casing from the influence of external magnetic waves, a diaphragm secured upon 30 the casing, a laminated permanent magnet

within the casing, electro-magnets connected to the poles of the permanent magnet for vibrating the diaphragm, a bridging device secured upon the casing, and a transmitting button carried by said device and including 35 an electrode fixed relative to said device, a movable electrode connected to and movable with the diaphragm, and a granular conducting material interposed between the electrodes. 40

2. A telephone relay including a casing, a lining therein for shielding the contents of the casing from the influence of external magnetic waves, a laminated permanent magnet within the casing, a diaphragm, 45 electromagnets secured to the poles of the permanent magnet for vibrating the diaphragm, a transmitting button mounted within the casing and including a fixed electrode; an electrode movable with the dia- 50 phragm, and a variable resistance material interposed between the electrodes.

In testimony that I claim the foregoing as my own, I have hereto affixed my signature in the presence of two witnesses.

CHARLES D. MORRIS.
